UNITED STATES PATENT OFFICE.

MORTIMER C. ROSENFELD, OF CLEVELAND, OHIO.

PIN FOR ELECTRICAL WORK.

1,176,927.

Specification of Letters Patent. Patented Mar. 28, 1916.

Application filed September 27, 1912. Serial No. 722,634.

To all whom it may concern:

Be it known that I, MORTIMER C. ROSENFELD, a citizen of the United States, resident of Cleveland, county of Cuyahoga, and State of Ohio, have invented a new and useful Improvement in Pins for Electrical Work, of which the following is a specification, the principle of the invention being herein explained, and the best mode in which I have 10 contemplated applying that principle, so as to distinguish it from other inventions.

My invention relates to devices for carrying the insulators which directly support the wires or cables carrying an electrical 15 current, and which devices are themselves secured to the cross-arm of a supporting pole. These devices are usually referred to in the art as "cross-arm pins."

The object of the invention is to provide 20 a pin of the described character which may be economically manufactured and which will be efficient in its use.

The said invention consists of means hereinafter fully described and particularly 25 pointed out in the claim.

In the annexed drawing:—Figure 1 represents an axial section of a pin embodying my invention and Fig. 2 represents a bottom plan thereof.

30 The illustrated device comprises a main or body portion A of general frusto-conical construction and preferably hollow, of cast-iron, in the outer end of which is embedded, and thus securely fixed, a steel male-threaded member B. This member is so secured by casting the metal of the member A around its base, and providing a groove a in the latter for insuring its permanency of position. The male-thread is provided for the 35 reception of the glass or porcelain insulator.

The opposite or inner end of the member A is formed with the annular flange a' and adjacent thereto is the transverse integral spider a². The middle of the latter is formed

with the boss a³ extending toward but not 45 reaching the plane of the face of said flange. This boss is formed with the internally threaded bore a⁴ for receiving the bolt C which secures the pin to the cross-arm D.

By means of the above-described construction, it will be seen that by providing the steel member B, all the advantages of the use of such metal is contained while the main structure is made of the cheaper iron capable of being readily cast, and since obviously the said member may be comparatively short, a minimum amount of steel is used.

By providing the transverse and female-threaded member a², ready means are provided for fastening the whole pin securely to the cross-arm, while at the same time only the face of the flange is in contact with the latter, thereby permitting the pin to be secured rigidly and so as to be devoid of 65 movement or "wabbling."

Having fully described my invention, what I claim and desire to obtain by Letters Patent is:—

As a new article of manufacture, the combination of a unitary structure for electrical work comprising a hollow main conical member of cast metal and formed with an annular flange at its base; a male threaded member of steel having its base embodied 70 in the metal of the outer end of said main-member; a transverse spider cast integral with the latter, adjacent to but removed some distance inwardly from said base end; said spider being formed with a centrally 75 located threaded bore co-axial with said male threaded member.

Signed by me, this 16th day of September, 1912.

MORTIMER C. ROSENFELD.
